UNITED STATES PATENT OFFICE.

MARIE KIRKPATRICK, OF GRAND RAPIDS, MICHIGAN, ASSIGNOR TO FICKS REED COMPANY, OF CINCINNATI, OHIO, A CORPORATION OF OHIO.

DESIGN FOR A CHAIR.

Application filed April 8, 1929. Serial No. 30,799. Term of patent $3\frac{1}{2}$ years.

To all whom it may concern:

Be it known that I, MARIE KIRKPATRICK, a citizen of United States of America, and a resident of Grand Rapids, in the county of Kent and State of Michigan, have invented a new, original, and ornamental Design for a Chair, of which the following is a specification, reference being made to the accompanying drawing, forming a part thereof.

The figure is a perspective view of a chair, showing my new design.

I claim:

The ornamental design for a chair, as shown.

MARIE KIRKPATRICK.
